UNITED STATES PATENT OFFICE.

WILLIAM A. PARMENTER, OF BROCKTON, MASSACHUSETTS, ASSIGNOR TO
CHARLES S. PIERCE, OF BROCKTON, MASSACHUSETTS.

BUFFING-MACHINE.

SPECIFICATION forming part of Letters Patent No. 776,417, dated November 29, 1904.

Application filed February 19, 1904. Serial No. 194,320. (No model.)

To all whom it may concern:

Be it known that I, WILLIAM A. PARMENTER, a citizen of the United States, residing at Brockton, in the county of Plymouth and State 5 of Massachusetts, have invented an Improvement in Buffing-Machines, of which the following description, in connection with the accompanying drawings, is a specification, like characters on the drawings representing like 10 parts.

This invention has for its object the production of a novel buffing-machine, the mechanism of which as I have herein chosen to illustrate my invention is adapted for buffing 15 leather used in the production of boots and shoes, especially in box-toes and heel-stiffeners.

My novel machine includes a traveling bed provided with one or more stock-supports on 20 which the pieces of stock of desired shape are laid, the stock-support in its movement causing the stock to be subjected to one or more rotatable buffing-cylinders, preferably two cylinders, one cylinder—the first one to 25 act—having a coarser abrasive surface than the second cylinder. The shaped pieces of stock to be buffed are laid on the stock-supports and are positioned thereon by positioning means, shown as retractile or spring-sus- 30 tained pins which are automatically withdrawn as the stock passes under the buffing-cylinders, the withdrawal of the pins taking place only at such time and at such points with relation to the movement of the stock 35 under the cylinders as will prevent their contact with the periphery of the cylinder where tangent to the stock, it being understood, should said pins not be withdrawn, that the cylinders would strike the pins and the action 40 of the cylinder in abrading the stock to a thin edge could not be done. The positioning means by acting against the edges of the stock maintain the same correctly on the stock-supports and the stock may be correctly 45 presented to the buffing-cylinders, and by withdrawing only a part of the pins at any one time the remaining pins are enabled to prevent any slipping or displacement of the stock on the several stock-supports. The

framework of the machine outside the trav- 50 eling bed sustains a series of rolling pressers that act on the upper side of the stock to keep it seated on the stock-support. In connection with the buffing-cylinders I employ stock-holding rollers, made as conical sleeves 55 loosely sustained on guides and acted upon at one end by a spring which permits the conical sleeves in their rotation to move longitudinally of the guide-rods as the work varies in thickness. Between the first holding- 60 roller or conical sleeve to act on the stock and the buffing-cylinder I employ a series of spring-fingers that bear on the stock close to the point where the buffing-cylinder contacts therewith.

Figure 1 in side elevation represents a machine embodying my invention to be herein described. Fig. 2 is a view looking at the left of Fig. 1, chiefly to show the gearing employed for rotating the buffing-cylinders. Fig. 3 is 70 a section in the line α , Fig. 4, showing one of the pressers acting upon the stock to be buffed, the latter lying on the stock-support. Fig. 4 is a detail showing the movable traveling bed, 75 its stock-supports, presser-rollers, the stock-holding rollers, and spring-fingers to be hereinafter referred to. Fig. 5 is a detail showing in dotted lines a buffing-cylinder and holding-rollers, the latter acting on stock on a stock-support supposed to be moving under 80 the buffing-roller. Fig. 6 is a detail showing one of the stock-supports and stock-discharging means. Fig. 7 shows a piece of stock that has been skived about its edges and to be buffed. Fig. 8 shows the stock buffed or made thinner 85 that it may be used for a toe-cap or in a heel-stiffener or other place in a shoe.

The framework of the machine comprises a plate A, upon which is erected a bearing-stand A' for sustaining an upright shaft A², having 90 a worm-toothed gear A³, that is engaged and rotated by a worm A⁴ on a shaft A⁵, sustained in suitable depending bearings A⁶ and having a belt-wheel A⁷, over which is extended a belt B¹⁰, (represented by dotted lines,) said belt revolving a brush B, to be described. The shaft A⁵ will be driven from any counter-shaft through suitable fast and loose or usual clutch- 95

pulleys, (represented by dotted lines A⁸), said pulleys being of any usual or suitable kind and not of my invention.

The plate A has erected on it two stands B', 5 one only being shown in Fig. 1, and two like stands B² B³. These stands sustain like horizontal shafts B⁴, having each at one end a bevel-pinion B⁵, that is engaged and rotated by a bevel-wheel B⁶, fast on the shaft A². Each 10 shaft B⁴, constituting the prime shaft for driving each of the two sets of stock-holding rollers at opposite sides of the like buffering-cylinders B⁷ B⁸, has at its outer end a pinion C, (see Fig. 2) through intermediate gears C' C² 15 and smaller gears C³ C⁴ rotate like shafts C⁵, sustained in boxes 20 in legs extended from said stands and in like depending legs C⁶, forked, as represented in Fig. 1, and held in position by screws m. The bearings 21 are 20 acted upon by springs 3^x, that serve normally to maintain the outer ends of said shafts in a yielding manner that the conical sleeves a, carried thereby and splined loosely thereon, may adapt themselves to the thickness of the stock 25 being buffed, said conical sleeves being also free to slide longitudinally on said shafts against the action of springs a' according to variation in thickness of the stock.

The overhanging part B^x of each upright 30 has a stud D, on which is mounted a yoke D', having bearings for the shafts D², on which are mounted the buffering-cylinders B⁷ B⁸, there being one such shaft for each cylinder. Each shaft has at its outer end a suitable belt-pulley D³, over which may be extended a belt 35 driven from any usual counter-shaft that the buffering-cylinders may be rotated at any desired speed, the first buffering-cylinder, as B⁷, to act on the stock being preferably coated with a coarser buffering or abrasive substance than that 40 carried by the buffering-cylinder B⁸, it being desirable that the first cylinder to act may take off a larger amount of stock in reducing the thickness thereof by buffering, the second cylinder 45 to act, covered with finer material, polishing and leaving a smoother surface than the first cylinder to act. By pivoting the yokes D' on the overhanging portion B^x of the uprights and providing the adjusting devices D⁴, shown as screws, the yokes may be adjusted 50 vertically or tipped to adapt the peripheries of the buffering-cylinders to just the position desired according to the work being acted upon.

The upper end of shaft A² receives upon it 55 the hub of the revolving table D⁵, so that said table is rotated by said shaft at a speed determined by the shaft A⁵. The under side of the bed, especially at points opposite where the buffering-cylinders act, is sustained by antifriction-rollers mounted in brackets b', held in position by set-screws b². The bed D⁵ sustains 60 a series of stock-supports d d' d'' d³, each having end legs d⁴, provided with dowel-pins that enter the bed, (see dotted lines, Figs. 5 and 65 6,) said supports being held in working posi-

tion thereon by turn-buttons d¹⁰, extended from vertical shafts having handles d¹², said buttons engaging lips d¹³, connected with the under side of each support. The upper sides of these work-supports are cupped or worked 70 out, as shown in the bed d', (represented in cross-section, Fig. 3,) the space so made receiving a piece of stock d⁵, which has been skived about its edge, as at d^{5x}, Fig. 7, upon its flesh side. The hair or grain side of the 75 piece of stock is laid on the stock-support and in said depression. The buffering-cylinders will thereafter act to buff the flesh side of the stock and leave it in the condition Fig. 8, where it will be seen that the inclined face made by 80 skiving the stock, as shown in Fig. 7, is carried almost or substantially to the center portion of the stock. Each stock-support is provided with a series of holes, that receive 85 loosely a series of positioning devices, shown as pins, numbered from 2 to 9, said pins being arranged in pairs, as 2 3, 4 5, &c. Each pair of pins is jointed to an arm e of a rock-shaft e', sustained in the work-supports, one end of each of said rock-shafts being bent to form 90 arms e², against which bear springs e³, said springs acting normally to hold said rock-shafts in position to keep said pairs of pins in their elevated positions to contact with the edge of the stock d⁵ and constitute positioning 95 means therefor. As the bed is moved in the direction of the arrow, Fig. 4, the pairs of pins 2 3, 4 5, &c., must be retracted as the stock passes under the buffering-cylinders to thereby obviate injuring the buffering-material 100 and while the periphery of each of said cylinders acts transversely of the stock in the line of said pins. To do this, I have provided pin-retracting means, shown as cams f, fixed on the stationary part of the framework, against 105 which said arms e² strike one after the other that said pairs of pins may be retracted at the proper times, so that they cannot be struck by the buffering-cylinders.

The bottom or frame plate A has erected 110 upon it posts f', provided at their upper ends with bars f², to which may be connected by screws yielding or springy arms f³, carrying presser-rollers f⁴, that contact with the upper 115 side of the stock near one edge, as shown in Fig. 4, as the stock approaches each buffering-cylinder.

One of the sleeve-like conical rollers a in front of each buffering-cylinder is acted upon at 120 its outer end by a spring a', while the roller located behind the buffering-cylinder is acted upon at its inner end by a spring a^x. These rollers are splined on the shafts C⁵, rotated by means heretofore described, so that said rollers are rotated thereby, and said springs by 125 sliding the rollers on said shafts enable the rollers to adapt themselves to any variations in the thickness of the separate pieces of stock coming under the buffering-cylinders.

Between the rollers a in front of each buff- 130

ing-cylinder and the point where the periphery of the buffing-cylinder contacts with the stock I have arranged a series of spring-fingers g , under which the stock is moved, said fingers maintaining the stock closely in contact with the stock-support. The stock will be supposed to have been buffed to the desired thickness after having passed the second cylinder; but it will be understood that I may 5 employ any desired number of buffing-cylinders according to the work to be done, and thereafter the buffed piece of stock should be discharged from the machine. I have provided means for effecting the discharge of the 10 stock automatically and have shown one form of means for that purpose. The means shown comprises a finger g' , (see full lines, Fig. 6, and dotted lines, Fig. 5,) contained in a slot in the work-support. The finger is connected with 15 a rock-shaft g^2 , (see Figs. 4 and 6,) having fast on one end thereof a dog g^3 , that is acted upon by a spring g^4 , said spring when controlling said dog normally retaining the finger depressed in the slot in the work-support. 20

25 When in the revolution of the bed a work-support has passed the last buffing-cylinder and the work has been fully buffed, the upper end of said dog meets the under side of an in-turned portion of a finger g^6 and is turned by 30 said contact to turn the rock-shaft and raise the finger into the position Fig. 6, thus lifting the advancing end of the buffed piece of stock d^5 from the stock-support, as shown therein, so that as the bed continues to be 35 revolved the raised end of the stock is caught by the pick-off h , shown as a hook-shaped arm attached to a collar h' , fastened by a set-screw h^2 to a post h^3 , erected on the frame-plate A. After passing the buffing-cylinders I need 40 employ but one presser-roller h^4 to bear on the stock. The adjusting-screws D^4 are rotatably mounted in plates m^1 , connected to said over-hanging arm by set-screws m^2 .

I do not wish to limit this invention to the 45 exact means shown in the drawings for effecting the results described, as it will be obvious that my invention is susceptible of various modifications and yet be within the scope of the specification and the following claims, 50 which are intended to cover any mere modifications.

The stock after it has been buffed by the last buffing-cylinder is passed under the brush B, that is rotated by the crossed belt B^1 , driving its motion from a pulley A^7 on the 55 main driving-shaft A^8 .

Having described my invention, what I claim, and desire to secure by Letters Patent, is—

60 1. In a machine of the class described, a movable bed having a stock-support to sustain the stock, positioning devices to engage the edge of the stock on the stock-support, and means to withdraw said positioning devices from 65 contact with the edge of the stock.

2. In a machine of the class described, a movable bed having a stock-support provided with a plurality of positioning devices arranged in pairs, and means to withdraw said positioning devices in succession from contact with the 70 edges of the stock.

3. In a machine of the class described, a stock-support, a plurality of spring-sustained positioning devices, and means to withdraw said positioning devices successively at the 75 proper times.

4. In a machine of the class described, a movable bed having a plurality of stock-supports provided each with spring-supported positioning devices, means to move said bed and 80 its stock-supports, and means to withdraw said positioning devices.

5. In a machine of the class described, a bed having a series of stock-supports concaved at their upper sides, yielding positioning devices 85 to contact with the edges of and position said stock on said stock-supports, and means for buffing the face of the stock sustained by said stock-support.

6. In a machine of the class described, a bed 90 having a series of stock-supports concaved at their upper sides, yielding positioning devices to contact with the edges of and position said stock on said stock-supports, and a plurality of buffing-cylinders acting in succession on 95 the face of the stock sustained on said stock-supports.

7. In a machine of the class described, a bed having stock-supports to sustain stock to be buffed, a shaft, a conical sleeve mounted 100 thereon to contact with and roll over the stock, and a spring acting normally on one end of said sleeve to enable it to slide on said shaft and automatically adapt itself to the thickness of the stock.

8. In a machine of the class described, a bed having a stock-support to sustain stock to be buffed, a buffing-cylinder, means to rotate the same, conical sleeves located in front of and at the rear of said buffing-cylinder, and springs 110 acting on said conical sleeves to cause their peripheries to adapt themselves to variations in thickness of the stock being acted upon.

9. In a machine of the class described, a movable bed having stock-supports to sustain the 115 stock to be buffed, positioning devices to engage the edge of the stock on the stock-support, a buffing-cylinder, means to rotate the same, rollers at opposite sides said buffing-cylinder and adapted to roll over the stock in 120 front of and behind said cylinders, and means to withdraw said positioning devices from contact with the edge of the stock in line with the point where the buffing-cylinder acts.

10. In a machine of the class described, a 125 buffing-cylinder, tapered rollers at opposite sides thereof to roll over the stock, a movable bed carrying a plurality of stock-supports to sustain stock to be buffed, means to rotate said cylinder and move said bed with its stock-sup- 130

ports thereon, and a series of fingers to bear on the stock on its way under the buffing-cylinders at a point between said rollers.

11. In a machine of the class described, a 5 movable bed, a stock-support thereon recessed at its upper side to sustain stock, and provided with a series of holes, a series of sliding positioning devices in said holes, and means to automatically retract said positioning devices 10 during the movement of said stock-bed.

12. In a machine of the class described, a movable bed having a stock-support to sustain the stock to be buffed, positioning devices to engage the edge of the stock on the 15 stock-support, a buffing-cylinder to act upon the stock on the stock-support, means to withdraw said positioning devices from contact with the edge of the stock in the line of action of the buffing-cylinder thereon, and means for 20 automatically discharging the buffed stock from the machine.

13. In a machine of the class described, a

movable bed, a series of independent stock-supports, and means to clamp the same thereon, said stock-supports having a series of 25 holes, and pairs of slid able pins connected with rock-shafts, and means to move said rock-shafts automatically to retract said pins at the desired times.

14. In a machine of the class described, a 30 stock-support, a buffing-cylinder, and sustaining means therefor, said sustaining means having provision whereby it may be adjusted vertically and tipped to enable the surface of the buffing-cylinder to be located properly with 35 relation to the stock to be buffed.

In testimony whereof I have signed my name to this specification in the presence of two subscribing witnesses.

WILLIAM A. PARMENTER.
